DESIGN FOR A FLORAL CONTAINER

Roderic M. Koch, Evansville, Ind.

Application February 12, 1941, Serial No. 98,975

Term of patent 14 years

To all whom it may concern:

Be it known that I, Roderic M. Koch, residing at Evansville, in the county of Vanderburgh and State of Indiana, have invented a new, original, and ornamental Design for a Floral Container, of which the following is a specification, reference being had to the accompanying drawing forming part thereof.

I claim:

The ornamental design for a floral container, as shown.

RODERIC M. KOCH.
